FIG. 2.

INVENTOR

David William Price

UNITED STATES PATENT OFFICE

106,409

DESIGN FOR A DRESS

David William Price, New York, N. Y.

Application August 18, 1937, Serial No. 71,162

Term of patent 3½ years

To all whom it may concern:

Be it known that I, David William Price, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the specific ornament member applied in the position and in combination with the dress shown.

I claim:

The ornamental design for a dress, substantially as shown and described.

DAVID WILLIAM PRICE.
